BY-PASS VALVE FOR LIQUID DISPENSERS

William H. D. Brouse, Toronto, Ontario, Canada,
assignor to Service Station Equipment Company Limited, Toronto, Ontario, Canada

Application November 22, 1933, Serial No. 699,149

9 Claims. (Cl. 103—42)

The principal objects of this invention are, to effect a saving in the installation of liquid dispensing pumps by providing a device which will require less power to operate the pump by the elimination of back pressures when the discharge from the pump is closed.

The principal features of the invention consist in the provision of a by-pass valve in a circulatory portion of a liquid dispensing system whereby the flow of the liquid through the pipes is utilized to effect the positive closing of the by-pass valve when the liquid is being dispensed and to effect the positive opening of the valve to permit the unrestricted flow of liquid through the by-pass with the consequent relief of stress on the pumping unit when the discharge is closed.

In the accompanying drawing, Figure 1 is a diagram illustrating the piping arrangement of a liquid dispensing unit equipped with my improved by-pass device.

Figure 2 is an enlarged longitudinal mid-sectional view through the by-pass valve.

Figure 3 is an enlarged longitudinal mid-sectional view of one of the inspirator nozzles used in co-operation with the by-pass valve.

In the dispensing of liquids and particularly that of gasoline, the direct discharge type of pump is being extensively used, that is, the type wherein the liquid is drawn from a supply tank by a suitable pump and is discharged through a meter to the dispensing nozzle.

Ordinarily upon the closing of the dispensing nozzle the full pressure of the pump is exerted against a by-pass valve which is normally spring loaded to resist the full head pressure of discharge and the motor is required to lift such valve against such resistance until the operation of the pump is arrested. The shock of this sudden back pressure is extremely severe upon the motor operating the pump and consequently requires a very heavy unit.

In the arrangement herein shown a by-pass valve is provided, the body 1 of which is formed with an inlet 2 and an outlet 3 between which is arranged a passage 4 closed by a valve 5.

The valve 5 is provided with a hollow cylindrical portion 6 which extends upwardly into a cylindrical cavity 7 formed in a plug 8 threaded into the top end of the valve.

A coil compression spring 9 is arranged within the hollow extension 6 to hold the valve downwardly to its seat.

The pressure of the spring 9 may be regulated by an adjustable block 10 threaded in the upper threaded end of the cavity 7 in the plug 8.

The upper end of the cavity 7 is closed by a cap screw 11.

A stem 12 is secured centrally in the lower end of the valve 5 and extends through a central circular opening 13 in a partition wall 14 arranged in the valve body below the inlet 2, and slidably mounted upon the lower reduced end 15 of said stem is a piston member 16 provided with a sleeve 17, the upper end of which abuts the shoulder 18 at the upper end of the reduced portion of the stem.

The piston 16 operates within a cylindrical cavity 19 arranged below the partition 14 and when the valve 5 is closed, said piston is held with its sleeve 17 engaging the shoulder 18 by a light coil compression spring 20 encircling the spindle below the piston and engaging a washer 21 secured in an adjustable position by a nut 22 threaded on the spindle.

An opening 23 is provided in the wall of the cylindrical cavity 19 communicating with the inner end thereof above the piston 16, the outer end of which is threaded to receive a pipe 24 and an opening 25 is connected with the lower end of the cylinder and communicates with the pipe 26.

The valve is operated under the influence of changes of pressure due to the application of a suction effected through either of the pipes 24 or 26. When suction is applied to the pipe 24 the piston 16 is caused to move upwardly lifting the valve 5 from its seat against the pressure of the spring 9 and a free flow of liquid from the inlet 2 to the outlet 3 of the by-pass valve is provided.

When suction is applied to the cylindrical cavity below the piston 16 through the pipe 26 and its communicating opening the valve 5 is drawn downwardly against the pressure of the liquid flow between the inlet and outlet and against the pressure of the bottom spring 20, so that the flow through the by-pass is arrested.

In order to accomplish this manipulation of the valve it is of course necessary to provide suitable suction means which are incidental to the flow of liquid through the system.

In the arrangement herein shown the liquid supply tank 27 is connected by a pipe 28 to the pump 29 which is of any suitable design and motor operated.

The discharge pipe 30 from the pump leads to a suitable metering device 31 and from thence the fluid is directed through a flexible hose and control nozzle 32.

Intermediate of the length of the pipe 30 I pro-

vide a Venturi tube 33 which has a short restricted passage 34 at the inlet and leading to an elongated divergent passage 35 and an opening 36 arranged at the throat is connected by the pipe 26 to the lower end of the by-pass cylinder.

5 A branch pipe 37 is connected to the pipe 30 between the pump 29 and the Venturi pipe or tube 33 and leads to the inlet opening 2 of the by-pass valve. Within this branch pipe is arranged a Venturi tube 38 similar to the Venturi tube 33 and the throat thereof is connected by the pipe 24 to the upper opening of the cylinder of the by-pass valve.

10 A branch pipe 39 connects the outlet 3 of the by-pass valve with the supply pipe 28 leading from the tank to the pump.

15 In the operation of this device, when the liquid is to be dispensed, the pump motor is started before the dispensing nozzle 32 is opened and as the various pipes of the unit are filled with liquid 20 the pressure of the pump causes the valve 5 to be lifted from its seat and a circulatory flow is commenced in the looped pipe structure containing the by-pass valve. The moment that the flow of liquid 25 commences a suction is established in the Venturi tube 38 which is conducted through the pipe 24 to the upper end of the cylinder cavity 19 of the by-pass valve and pulls upwardly on the piston 16 overcoming the resistance of the valve 30 spring and holding the valve open so that the liquid flows freely through the by-pass valve and return branch 39 to the tank.

25 It will be understood that the application of suction from the Venturi tube 38 to the upper side of the piston 16 causes the sleeve 17 thereof to engage the shoulder 18 and lift the valve concurrently with the first movement of the liquid through the said venturi and it will be further evident that in the arrangement shown and described, on the closing of the dispensing valve 32 the back pressure will momentarily back up through the opening 36 and pipe 26 exerting a positive pressure influence on the underside of the piston 16 which will greatly assist in the initial opening of the by-pass valve 5. The load 40 upon the pump is thus relieved practically instantaneously and the combined suction on the piston and the pressure of the liquid against the underside of the valve and piston lift the valve against the pressure of the spring 9 which may be adjusted in the manner described.

45 Immediately upon the opening of the discharge nozzle 32 pressure in the pipe 37 is immediately relieved and suction through the pipe 24 is discontinued while concurrently the flow of liquid through the Venturi tube 33 creates a suction 50 through the pipe 26 which communicates with the lower end of the cylinder cavity and draws downwardly upon the piston against the spring 20 for a certain distance before the pressure exerted is sufficient to effect the closing of the valve 5 against the pump pressure. This cushioning of the valve will prevent hammering and will ensure not only quietness of operation, but long life to 55 the valve seat.

60 With a device such as described installed in a liquid dispensing system back pressure on the motor operating the pump is also instantaneously relieved following the closing of the dispensing nozzle, and the by-pass is maintained open with the minimum of stress upon the pump permitting the free flow of liquid therethrough.

65 The preferred arrangement is shown with two vacuum creating devices operating to assist in operating the valve in both directions but it will 70

75 be understood that the valve may be spring loaded to resist the pressure of the discharge flow and a single venturi used to hold the valve open to relieve the motor of back pressure when the discharge is closed.

What I claim as my invention is:

1. In a liquid dispensing equipment having a motor operated pump and a by-pass for connecting the discharge and intake of the pump, and a spring-closed valve in said by-pass directly acted upon by the pressure of the pumped liquid to open the valve against the closing pressure of the spring and thereby permit the flow of liquid through the by-pass from the pump discharge back to the pump intake, the combination therewith of pressure responsive means co-operatively associated with the valve, and means co-operating with the flow of liquid through said by-pass and connected with said pressure responsive means to impart an operating pressure influence thereto and effective only after said valve has opened for assisting the opening movement of said valve.

2. In a liquid dispensing equipment having a motor operated pump and a by-pass connecting the discharge and intake of the pump, and a valve arranged in said by-pass to permit the flow of liquid from the pump discharge back to the intake, the combination therewith of suction creating means incorporated in the discharge from the pump, and displaceable means having a cushioned operative connection with said valve and displaced by said suction means for influencing said valve in accordance with the flow of liquid through the discharge.

3. In a liquid dispensing equipment having a motor operated pump and a by-pass connecting the discharge and intake of the pump and a valve arranged in said by-pass to permit the flow of liquid from the pump discharge back to the intake, the combination therewith of a cylinder associated with the casing of said valve having an opening therein, a spindle extending from the valve axially of said cylinder, a piston operating in said cylinder and slidably associated with said spindle, a suction creating device arranged in the discharge from the pump, a pipe leading from said suction creating device to the opening in said cylinder to effect the axial shifting of said piston through the flow of liquid through said suction creating device, stop means for limiting the sliding movement of the piston on the spindle in one direction, and resilient cushioning means resiliently opposing the sliding of the piston on the spindle in the reverse direction.

4. In a liquid dispensing equipment having a motor operated pump and a by-pass connecting the discharge and intake of the pump and a valve arranged in said by-pass to permit the flow of liquid from the pump discharge back to the intake, the combination therewith of a cylinder associated with the casing of said valve having openings at the top and bottom, a piston operating in said cylinder connected with the valve, a suction creating device arranged in the by-pass between the pump and the valve intake, a pipe connecting said suction device with one of the openings in said cylinder to effect the lifting of the valve, a suction creating device arranged in the discharge from the pump beyond the by-pass connection, and a pipe leading from the latter suction creating device to the other opening in said cylinder to urge the valve closed through the flow of liquid through the latter suction creating device.

5. In a liquid dispensing apparatus, the combination with a pump connected with the liquid

supply and a dispensing discharge and a by-pass connecting the discharge side of the pump with its intake, of a Venturi tube arranged in the by-pass, a valve arranged in said by-pass between said venturi and the pump intake, a piston operatively connected with the by-pass valve, a cylinder enclosing said piston, a pipe leading from the throat of said venturi and connected with said cylinder at one side of said piston, and suction creating means arranged in the pump discharge and connected with said cylinder on the other side of said piston and creating a suction in the cylinder on the said other side of said piston in accordance with the flow of liquid through the dispensing discharge.

6. In a liquid dispensing apparatus, the combination with a pump connected with the liquid supply and a dispensing discharge and a by-pass connecting the discharge side of the pump with its intake, of a Venturi tube arranged in the discharge between the pump and the dispensing end, a Venturi tube arranged in the by-pass, a by-pass valve arranged in said by-pass between the latter venturi and the pump intake, a piston operatively connected with the by-pass valve, a cylinder enclosing said piston, a pipe leading from the throat of one of said venturi tubes and connected with said cylinder at one side of said piston, and a pipe leading from the throat of the other of said Venturi tubes and connected with said cylinder at the other side of said piston.

7. In a liquid dispensing apparatus, a pump connected with a liquid supply and having a controlled discharge, a venturi arranged in said controlled discharge, a by-pass arranged between said pump and said venturi and connected to the pump intake and having a venturi therein, a valve casing arranged in said by-pass between the venturi therein and the pump intake, a spring loaded valve in said valve casing closing the passage therethrough, a cylinder arranged in said valve casing in alignment with

said valve, a spindle extending from said valve into said cylinder, a piston slidably mounted on said spindle and operating in said cylinder, a cushioning spring mounted on said spindle and engaging the outward side of said piston, a pipe connected with the lower end of said cylinder and leading to the throat of the venturi in the pump discharge, and a pipe connected with the upper end of said cylinder and leading to the throat of the venturi in the by-pass.

8. In a liquid dispensing equipment the combination of a motor driven pump, a dispensing conduit connected with the pump discharge and periodically opened to release the pumped liquid therefrom and thereafter closed to cut off further flow therefrom, a by-pass conduit extending between the pump discharge and intake, a valve controlling the flow of liquid through the by-pass and automatically closed during the release of fluid from said discharge, and means automatically controlling said by-pass valve in accordance with the difference in velocity flow of liquid in said dispensing conduit and by-pass.

9. In a liquid dispensing equipment the combination of a motor driven pump, a dispensing conduit connected with the pump discharge and periodically opened to release the pumped liquid therefrom and thereafter closed to cut off further flow therefrom, a by-pass conduit extending between the pump discharge and intake, a valve in said by-pass spring held closed against the dispensing pressure of said pump only when said dispensing conduit is open to discharge the pumped liquid and adapted to be forced open by the pumped liquid against the spring pressure immediately on the closing of the dispensing discharge to by-pass the undispensed liquid, and means imparting respectively opening and closing influences to said by-pass valve in accordance with the velocity of flow of the by-passed or dispensed liquid.
